GAME BOARD

Rene Lapierre, 33 Whorton Ave., Nutley, N.J. 07110

Filed Jan. 9, 1975, Ser. No. 539,693

Term of patent 14 years

Int. Cl. D21—01

U.S. Cl. D34—5 PB

FIG. 1

FIG. 2

FIG. 3

FIG. 1 is a plan view of the game board showing my new design;

FIG. 2 is an end view of the board; the opposing end being identical in appearance; and

FIG. 3 is a side view of the board; the other side being identical in appearance.

The figure is partly broken away to reveal the pockets.
I claim:

The ornamental design for a game board, as shown and described.
